UNITED STATES PATENT OFFICE.

HOWARD M. DUDLEY, OF PHILADELPHIA, PENNSYLVANIA.

DYEING-MACHINE.

1,280,188.

Specification of Letters Patent.

Patented Oct. 1, 1918.

Application filed September 24, 1917. Serial No. 192,897.

To all whom it may concern:

Be it known that I, HOWARD M. DUDLEY, a citizen of the United States, residing in the city of Philadelphia, county of Philadelphia, and State of Pennsylvania, have invented certain new and useful Improvements in Dyeing-Machines, of which the following is a full, clear, and exact specification.

10 The device of my invention relates to dyeing machines and refers particularly to machines suitable for the dyeing of piece goods or fabrics by forcing a dye liquid therethrough.

15 One object of my invention is a device whereby a fabric may be wound evenly upon, and unwound from, the dyeing cylinder without the removal of the latter.

Another object of my invention is a device 20 in which a dye liquid, or other liquid may be passed in opposite directions through the roll of fabric.

Another object of my invention is a foraminous cylinder or reel, upon which the 25 fabric is wound, of such a construction as to allow of equal penetration of a liquid.

Another object of my invention is a device in which the volume of a liquid is distributed equally over the surface of the 30 wound fabric.

These and other objects of my invention will be evident upon a consideration of my specification, drawings and claims.

In the dyeing of wound or rolled piece 35 goods and fabrics, it is essential that they be rolled evenly and uniformly, free from folds, and that all portions of the fabric be treated uniformly with the dye liquid and then uniformly washed to remove all excess 40 of dye liquid.

The device of my invention accomplishes these purposes by winding the fabric directly upon the dyeing reel in such a manner that it will not be disturbed, by supporting 45 the fabric in a manner that will subject the exterior of the roll to a maximum of dye liquid, by having foraminous means in the dyeing reel to allow of equal distribution of the dye liquid and by feeding the dye liquid 50 under uniform pressure to all portions of the fabric roll.

In the particular form of the device of my invention illustrated in the accompanying drawings, similar parts are designated 55 by similar numerals.

Figure 1 is a vertical cross-section of one form of my device.

Fig. 2 is an end elevation in the direction of the arrow 2 of Fig. 1, showing the winding roller in operative and inoperative position.

Fig. 3 is a cross-section through the line 3—3 of Fig. 1.

Fig. 4 is a broken side plan of the inner foraminous member of the dyeing reel.

Fig. 5 is a view in the direction of the arrow 5 of Fig. 4.

Fig. 6 is a cross-section through the line 6—6 of Fig. 4.

Fig. 7 is a top plan of a modified form of 70 the inner foraminous member of the dyeing reel.

Fig. 8 is a cross-section through the line 8—8 of Fig. 7.

Fig. 9 is a cross-section through the line 75 9—9 of Fig. 1.

Fig. 10 is an enlarged side plan view partly in cross-section of the testing device.

The particular form of the device of my invention illustrated in the accompanying drawings comprises a reel formed of a foraminous cylinder 10, fixedly attached to the cylindrical members 11, 12 and the annular flanges 13, 14. A conical shaped conduit 15 fixedly attached to the flange 14 converges 85 into the pipe 16, within which the pipe 17 is revoluble, a tight joint being formed by means of the bushing 18. The conduit 15 is revolubly supported by the bracket 19. The pipe 17 is connected with a source of dye 90 liquid and water not shown. The annular member 20, fixedly attached to the member 11, carries a series of conduits 21, 21 extending inwardly of the reel from the chamber 22 and then extending outwardly toward 95 the inner face of the foraminous cylinder 10, a chamber 23 being situated between the inner face of the foraminous plate 10 and the inner openings of the conduits 21, 21. The member 20 is also fixedly attached to the 100 cogged wheel 24, which meshes with the worm gear 25 carried by the shaft 26 which is connected to a source of power. The hollow member 27, fixedly attached to the member 20 carries the pipe 28 which is revoluble 105 therein and which is connected with a source of dye liquid and water not shown. A tight joint is maintained between the members 27 and 28 by the bushing 29. Two annular cover members capable of removable place- 110

ment between the flanges 13 and 14 comprise the exterior members 30, 30^A fixedly attached to the two end members 31, 32, 31^A, 32^A respectively. Within the two cover members are a series of conduits 33, 33, 33^A, 33^A, 5 connecting the conduit 15 with the chambers 34, 34^A the chambers 34, 34^A containing a series of longitudinally parallel blades 35, 35, 35^A, 35^A. The walls of the conduits 21, 21 and 10 33, 33 are supported by the supporting members 21', 21' and 33', 33' respectively. The two cover members may be attached to each other by means of the bolts 36, 36. The reel portion of the device is inclosed in a reception 15 tackle formed by the bottom 37 and the top 38 hingedly attached thereto by the hinge 39, the top and bottom being capable of attachment to each other by means of the bolts 40, 40. Revolvable within, and removable from, 20 the openings 41, 41 of the supports 42, 42 is a roller 43 capable of abutment upon the foraminous cylinder 10, the roller 43 being capable of removal by means of the hoist-hook 44. A pipe 70 carrying the valve 71 25 is introduced into the bottom 37.

The reel carries a testing device, the construction of which is shown in Fig. 10. This testing device consists of members similar and proportionate to the larger reel, and 30 the numerals upon Fig. 10 correspond to those upon Fig. 1. One end of the cylinder is connected to the pipe 52 carrying the valve 53 by means of the coupling 54, and the other end of the cylinder is connected to 35 the pipe 55 carrying the valve 56 by means of the coupling 57. The pipe 52 connects with the chamber 34, and the pipe 55 connects with the chamber 23.

The foraminous cylinder 10 comprises a 40 series of parallel and intersecting flat bars 60, 60 forming the hollow squares 61, 61. Each bar 60, 60 carries an outwardly extended triangular member 62, 62. The apices of the triangular members 62, 62 support the fabric while a liquid has free passage through the openings 61, 61 and between the triangular members.

In the modified form of the foraminous cylinder 10 illustrated in Figs. 7 and 8, the 50 triangular members 63, 63 around the sides of each hollow square 60, 60 are brought to a common apex 64, the basis of the triangular members 63, 63 being less than the length of the side squares.

55 The operation of the device is as follows:—

The top 38 is raised as indicated in Fig. 2, the roller 42 placed within the openings 41, 41, and the reel revolved, thus winding the 60 fabric 100 thereon. Similar fabric 101 is wound upon the reel of the testing device. The roller 42 is then removed by means of the hoisting hood 44 and the two cover members clamped around the fabric 100 by means 65 of the bolts 36, 36 and the top 38 closed upon

the bottom 37 and clamped thereto by means of the bolts 40, 40. All of the valves are closed with the exception of valves 53 and 56, dye liquid is then introduced into the pipe 28 thence passing through the chamber 22, the conduits 21, 21, the chamber 23, the foraminous cylinder 10, the fabric 100, the chambers 34, 34^A, the conduits 33, 33, 33^A, 33^A, the conical conduit 15 and the pipe 17 to a reserve tank not shown. At the same 75 time the dye liquid passes through the pipe 55 of the testing device and outwardly through the fabric 101. When desirable, the liquid may be forced in a reverse direction through the fabric 100 by forcing the 80 liquid into the device through the pipe 17. From time to time the condition of the fabric 101 in the testing device is examined by closing valves 53 and 56 and releasing the testing reel by uncoupling the couplings 54 85 and 57, thus not interrupting the passage of the liquid through the larger device. When the dyeing operation is completed, the fabric may be washed by forcing water through the pipes 28 and 17 as described above. 90

I do not limit myself to the particular size, shape, number or arrangement of parts as described and shown, all of which may be varied without going beyond the scope of my invention as described and claimed. 95

What I claim is:—

1. In a dyeing machine, in combination, a foraminous cylinder capable of having a fabric wound thereon, imperforate flange ends integral with the cylinder, a series of conduits capable of placement around the exterior of the fabric roll, means connecting the conduits with a source of liquid supply and means for forcing a liquid through the conduits and the fabric. 100

2. In a dyeing machine, in combination, a foraminous cylinder capable of having a fabric wound thereon, imperforate flange ends integral with the cylinder, a series of conduits within the foraminous cylinder, a removable series of conduits capable of placement around the fabric roll, means for connecting the series of conduits with a source of liquid supply and means for forcing a liquid through either series of conduits, the fabric roll and the other series of conduits. 110

3. In a dyeing machine, in combination, a foraminous cylinder capable of having a fabric wound thereon, imperforate flange ends integral with the cylinder, a removable series of conduits capable of placement around the fabric roll and between the flanges, means connecting the series of conduits with a source of liquid supply, a second series of conduits within the cylinder, means for connecting the second series of conduits with a second source of liquid supply, means for revolving the cylinder and the conduits and means for forcing a liquid through 125 130 135

either series of conduits, the cylinder, a fabric roll and the other series of conduits during the revolution of the reel and conduits.

5 4. In a dyeing machine, in combination, a foraminous cylinder having outwardly extended members capable of having a fabric wound thereon, imperforate flange ends integral with the cylinder, a removable series 10 of conduits capable of placement around and spaced from the cylinder and between the flanges, means integral with a flange for connecting the series of conduits with a source of liquid supply, a chamber within 15 the cylinder, a second series of conduits connecting the chamber with a source of liquid supply, means for revolving the cylinder, fabric roll and conduits and means for forcing a liquid through either series of conduits 20 and the fabric roll during the revolution of the reel.

5. In a dyeing machine, in combination, a foraminous cylinder having outwardly extended members capable of having a fabric 25 wound thereon, an imperforate flange at each end of the cylinder integral therewith, a removable series of conduits capable of placement around the cylinder and carrying a series of inwardly extended parallel plates, 30 means for connecting the conduits with a source of liquid supply, a second series of conduits within the cylinder and covering the inner face thereof, means for connecting the second series of conduits with a source 35 of liquid supply, means for revolving the cylinder and the conduits, and means for forcing a liquid through the device in either direction.

6. In a dyeing machine, in combination, a 40 receptacle, a foraminous cylinder having outwardly extended members capable of having a fabric wound thereon, imperforate flange ends integral with the cylinder, means whereby a liquid can be forced in opposite 45 directions through a fabric wound upon the cylinder, a smaller testing device comprising a foraminous cylinder with integral imperforate flange ends and means whereby a liquid may be passed through a fabric wound

upon the cylinder in the testing device, at 50 the same time the liquid is passed through the larger cylinder in either direction.

7. In a dyeing machine, in combination, a foraminous cylinder having outwardly extended members capable of having a fabric 55 wound thereon, imperforate flange ends integral with the cylinder, a removable series of conduits capable of placement around and spaced from the cylinder and between the flanges, means integral with a flange for connecting the series of conduits with a source of liquid supply, a chamber within the cylinder, a second series of conduits connecting the chamber with a source of liquid supply, means for revolving the cylinder, fabric roll 60 and conduits and means for forcing a liquid through either series of conduits and the fabric roll during the revolution of the reel, a smaller testing device comprising a foraminous cylinder with integral imperforate 65 flange ends and means whereby a liquid may be passed through a fabric wound upon the cylinder in the testing device, at the same time, the liquid is passed through the larger cylinder in either direction. 70

8. In a dyeing machine, in combination, a foraminous cylinder capable of having a fabric wound thereon, imperforate flange ends integral with the cylinder, a series of conduits capable of placement around the 80 exterior of the fabric roll, a second series of conduits within the foraminous cylinder, means for connecting each series of conduits with a source of liquid supply, and means for forcing a liquid through either series of 85 conduits, the fabric roll and the other series of conduits, a smaller testing device comprising a foraminous cylinder with integral imperforate flange ends and means whereby a liquid may be passed through a fabric 90 wound upon the cylinder in the testing device, at the same time, the liquid is passed through the larger cylinder in either direction.

Signed at Phila., in the county of Phila. 95 and State of Penna., August, 1917.

HOWARD M. DUDLEY.
